ELEVATOR CONTROL SYSTEM

Edwin H. Vedder, Swissvale, Pa., assignor to
Westinghouse Electric & Manufacturing Com-
pany, East Pittsburgh, Pa., a corporation of
Pennsylvania

Application November 13, 1934, Serial No. 752,798

13 Claims. (Cl. 187—29)

My invention relates, generally, to elevator systems, and it has particular relation to elevator systems for controlling the operation of a motor employed to operate the elevator car in a 5 hatchway.

In an elevator control system it is desirable to use light-sensitive devices, since they are simple in construction, instantaneous in operation, light in weight and may be readily carried 10 on a car in proper relation to the remaining apparatus. When such devices are employed, it is unnecessary to use cams or sliding contacts for controlling the operation of the elevator car.

An elevator system employing light-sensitive 15 devices is illustrated in Patent No. 1,769,054 to W. F. Eames, issued July 1, 1930, and in Patent No. 1,865,937 to H. W. Mattingly, issued July 5, 1932, both of which patents are assigned to the assignee of this application. It has been desir- 20 able, however, to improve upon the control system and apparatus shown in the patents and on the control systems and apparatus known to those skilled in the art. For that purpose, the control system and apparatus illustrated and 25 described herein have been made.

The object of my invention, generally stated, is to provide an elevator control system which shall be simple and efficient in operation and which may be readily and economically manu- 30 factured and installed.

The principal object of my invention is to provide for employing light-sensitive devices for controlling the operation of an elevator car.

An important object of my invention is to 35 provide for initiating a slow-down sequence for a motor operated elevator car to bring the car to rest at a desired floor level.

A further object of my invention is to provide for increasing the sensitivity and accuracy of 40 light-sensitive devices used for controlling the operation of a motor operated elevator car.

Still another object of my invention is to provide for preventing the functioning of a light- 45 sensitive system used for controlling the operation of a motor-operated elevator car, except at such times as it is desired to have the system operated.

Still another object of my invention is to pro- 50 vide for preventing the application of frequencies above a predetermined frequency and currents having steep wave fronts to a space- discharge device used in conjunction with light- sensitive equipment for controlling the func- 55 tioning of a motor-operated elevator car.

Other objects of my invention will in part be obvious and in part appear hereinafter.

Accordingly, my invention is disclosed in the embodiment hereof shown in the accompanying drawing and comprises the features of construction, combination of elements and arrangement of parts which will be exemplified in the construction hereinafter set forth and the scope of the application of which will be indicated in the appended claims. 5

For a more complete understanding of the nature and scope of my invention, reference may be had to the following detailed description taken in connection with the accompanying drawing, in which the single figure diagrammatically 10 represents a concrete embodiment of my invention. 15

According to my invention, an elevator car, which is movable in a hatchway by means of a motor, is provided with a light-sensitive unit. 20 This unit comprises a light source arranged to illuminate a photo-electric cell. The photo-electric cell is connected to control the functioning of a space discharge device or grid glow tube. When the photo-electric cell is illuminated, an 25 energizing potential is applied to the grid glow tube and the latter remains in the non-conducting state. However, as soon as the rays of light falling on the photo-electric cell are intercepted, the grid glow tube is rendered conducting. 30

In order to intercept the rays of light falling on the photo-electric cell, operating shields are placed in the hatchway. A shield is provided individual to each floor and is so spaced relative to the light-sensitive unit carried by the car, 35 that the desired functioning thereof may take place in sufficient time to cause the car to be brought to the level of the floor.

As soon as the grid glow tube is rendered conducting, the operating winding of a slow-down 40 relay is energized. The operation of this relay initiates a slow-down sequence for stopping the motor, which operates the elevator car at the proper rate, by any suitable well known means.

In order to ensure that the photo-electric cell 45 is illuminated before the grid glow tube is energized with a view to preventing a false operation thereof, the light source is energized as soon as the car approaches the floor where a call is registered and a predetermined time thereafter the grid glow tube is energized. This time delay is desirable in order to permit the light source, which usually is an incandescent lamp, to be brought to its operating brilliancy for the purpose of energizing the photo-electric cell to pre- 50

vent the grid glow tube from becoming conducting.

The grid glow tube is connected for energization to the secondary winding of a transformer; 5 the circuit including the operating winding of the slow-down relay and the grid glow tube. In view of the fact that the grid glow tube is a highly sensitive device and may be rendered conducting under certain conditions when such operation is 10 not desired, it has been found highly desirable to complete the energizing circuit to the grid glow tube by contact members interposed in the circuit including the secondary winding of the transformer rather than in the primary winding thereof. 15 If the energizing circuit for the grid glow tube is completed in the primary winding of the transformer, it has been found that the transient effects due to various magnetizations of the iron core of the transformer may be sufficient to ionize 20 the gas in the grid glow tube and to cause it to become conducting at a time when such action is not desired.

Since the light sensitive unit is mounted on the car while the remaining apparatus is mounted 25 in the penthouse, it is necessary to provide connections therebetween by means of conductors which are free to swing in the hatchway, as will be readily understood. These conductors function in somewhat the same manner as the antenna 30 of a radio receiving set and in many instances high-frequency currents are induced therein due to switching conditions in the control system of the elevator or adjacent apparatus. These high-frequency currents, in some instances, are sufficient 35 to cause ionization in the grid glow tube and as a result it becomes conducting. In order to avoid the false operation of the unit as a result of the superimposed high frequency, a filter is provided and connected in circuit with the grid 40 glow tube.

The filter not only prevents the application of high-frequency currents to the grid glow tube, which would tend to ionize the gas therein, but it also prevents the application to the grid glow 45 tube of the steep wave front of the control current, and, as a result, causes the grid glow tube to be responsive only to the control of the photo-electric cell.

For the sake of clarity and in order to reduce 50 the circuit connections and complications thereof to a minimum, I have illustrated my invention in schematic form. No attempt has been made to show the elevator car or associated control equipment other than that which is directly affected by the control system which is organized 55 in accordance with my invention. It will be readily appreciated by those skilled in the art that any of the various forms of control systems may be employed for controlling the operation 60 of the motor which is used for operating the elevator car.

Referring now particularly to the single figure of the drawing, the reference character 1 designates, generally, a light-sensitive unit which is 65 arranged to be carried on an elevator car. This unit comprises a light source 2, which may be a standard incandescent lamp, a photo-electric cell 3 and a space-discharge device or grid glow tube 4. As illustrated, the grid glow tube 4 is provided 70 with an anode 5, a cathode 6, a grid 7 and a shielding electrode 8. The particular construction of the grid glow tube 4 is set forth, in detail, in Patent No. 1,939,063, to D. D. Knowles, issued December 12, 1933, and assigned to the assignee 75 of this application. It will be understood, how-

ever, that any other suitable type of discharge device may be provided without departing from the scope of this invention.

It will be observed that the shielding electrode 8 is connected through a resistor 9 to the cathode 5 6 for a purpose which is fully set forth in the aforesaid patent to Knowles. It will also be noted that the photo-electric cell 3 is connected in series circuit relation with a capacitor 10 and a resistor 11 and between the anode 5 and the cathode 6. 10 It will also be noted that the common terminal between the capacitor 10 and the photo-electric cell 3 is connected to the grid 7. When the photo-electric cell 3 is illuminated, the resistance thereof is at a minimum and the grid 7 and cathode 6 15 are at substantially the same potential. When the light rays falling on the photo-electric cell are intercepted this condition no longer exists, and with operating potential applied between the anode 5 and the cathode 6, the grid glow tube 4 20 is rendered conducting.

In order to prevent the application of high-frequency currents and currents having steep wave fronts to the grid glow tube 4, an inductor 12 is provided. A capacitor 13 is connected in 25 shunt circuit relation with the inductor 12 and the grid glow tube 4, in order to by-pass the high frequency currents, which would otherwise pass through the grid glow tube 4 and might cause its ionization and its subsequent breakdown. 30

In order to intercept the light rays from the source 2, which fall on the photo-electric cell 3, an operating shield 14 is provided in the hatchway. A shield 14 is provided individual to each floor and, when it occupies the position 35 represented by the dotted lines between the light source 2 and the photo-electric cell 3, the rays falling on the latter are intercepted, the grid 7 no longer remains at the same potential as the cathode 6 and the grid glow tube 4 becomes 40 conducting.

As soon as the grid glow tube 4 becomes conducting, an operating winding 16w of a slow-down relay is energized. Suitable circuits, not shown, are then completed for initiating the 45 slow-down sequence for the elevator motor. This sequence may be controlled by additional light-sensitive units similar to that illustrated herein or it may be controlled by any other suitable control system. Since the system for effecting 50 the slow-down sequence forms no part of this invention, only the operating winding 16w of the slow-down relay has been illustrated herein.

It will be observed that the operating winding 16w is energized from the secondary winding 18 55 of a transformer shown generally at 19, the primary winding 20 of which is connected for energization between conductors 21 and 22. The conductors 21 and 22 may be connected to a suitable source of alternating current such as a 60 source having, as illustrated, a voltage of 110 volts.

Connections between the apparatus in the penthouse and the circuit including the grid glow tube 4 are provided by means of conductors 65 23 and 24. These conductors, in the usual manner, are illustrated by dotted lines which indicate that they are the long flexible control conductors which are connected between the elevator car and the apparatus in the penthouse. 70 Similar conductors 25 and 26 are provided for connecting the light source 2 to the control conductors 21 and 22.

As soon as a call is registered on a floor, contact members 27a are closed. The circuits and 75

apparatus for closing contact members 27a are well known to those skilled in the art and, therefore, they will not be further illustrated or described herein. In response to the closing of 5 contact members 27a, a floor segment 28a is connected to the energized conductor 21. In like manner, if a call exists on another floor, contact members 27b, for instance, will be closed, connecting floor segment 28b to the energized 10 conductor 21.

As the car approaches the floor at which the call is registered, brush 29 engages the floor segment 28a and completes an obvious energizing circuit for the operating winding 30w of a 15 control relay through contact members 31a of a speed relay 31, which contact members are closed as long as the elevator car is in motion.

As soon as the operating winding 30w is energized, contact members 30a are closed to complete a holding circuit around the contact members 27a, floor segment 28a and brush 29. Operating winding 30w is maintained energized until its energizing circuit is opened at contact 20 members 31a when the car stops.

At contact members 30b, a circuit is completed for connecting the light source 2 across the energized conductors 21 and 22. On being energized, it illuminates the photo-electric cell 3 which, in turn, is effective to keep the grid 25 7 at the potential of the cathode 6.

As has been set forth hereinbefore, it is desirable to prevent the energization of the grid glow tube 4 until a predetermined time after the light source 2 has been energized. For this purpose, it is desirable to prevent the closure of contact members 30c, which are operated on energization of the operating winding 30w until some time after contact members 30b have been closed. Any suitable means may be provided 30 which will effect this time delay. I have illustrated diagrammatically a dashpot 32 which is associated with the contact members 30c and is arranged to prevent the closure thereof until a predetermined time after contact members 30b 35 are closed. It will be understood, however, that any other suitable type of time delay apparatus may be employed in order to prevent the energization of the grid glow tube 4, until after the photo-electric cell 3 has been fully illuminated.

It will be observed that the contact members 30c are provided in the circuit which includes the secondary winding 18 of the transformer 19 rather than in the circuit which includes the primary winding 20. These connections are 40 provided, as set forth hereinbefore, in order to reduce to a minimum the effect of transients in the circuit including the grid glow tube 4, which may result from the magnetic condition of the core of the transformer 19.

Since certain further changes may be made in the above construction and different embodiments of the invention may be made without departing from the scope thereof, it is intended that all matter contained in the above description or shown in the accompanying drawing shall be interpreted as illustrative and not in a limiting sense.

I claim as my invention:

1. In a control system for a motor-operated elevator car movable in a hatchway relative to a floor, in combination, light-sensitive means and a light source disposed in operative relation thereto and carried by the car, a transformer having a primary winding connected to a source of alternating current and a secondary winding, a con-

trol relay operable in response to a floor call and having contact members, said contact members being disposed on operation of said relay to effect the energization of said light source and to connect said secondary winding to energize said 5 light-sensitive means, a shield mounted in the hatchway for controlling the illumination of said light-sensitive means in accordance with the position of said car with reference to said floor, and a slow-down relay responsive to a predetermined 10 change of the condition of illumination of said light-sensitive means for effecting the stopping of the motor to bring the car to the floor level.

2. In a control system for a motor-operated elevator car movable in a hatchway relative to one or more floors, in combination; a light-controlled unit carried by the car including a light source and a light-sensitive device disposed in operative relation thereto, and a space-discharge device disposed to be rendered conducting when 15 said light-sensitive device is in a predetermined condition of illumination; a transformer having a primary winding connected to a source of alternating current and a secondary winding, control means operable in response to a floor call to connect said secondary winding for energizing said space-discharge device, a shield mounted in the hatchway for controlling the illumination of said light-sensitive means in accordance with the position of said car with reference to said floor, and a slow-down relay disposed to be operated in 20 response to a predetermined change of the condition of illumination of said light-sensitive means for effecting the stopping of the motor to bring the car to the floor level.

3. In a control system for a motor-operated elevator car movable in a hatchway relative to one or more floors, in combination; a light-controlled unit carried by the car including a light source and a light-sensitive device disposed in operative 25 relation thereto, and a space-discharge device disposed to be rendered conducting when said light-sensitive device is in a predetermined condition of illumination; a transformer having a primary winding connected to a source of alternating 30 current and a secondary winding, control means operable in response to a floor call and having a plurality of sets of contact members, one of said sets of contact members being disposed to effect the energization of said light source and another 35 of said sets of contact members being disposed to connect said secondary winding to energize said space-discharge device, a shield mounted in the hatchway for controlling the illumination of said light-sensitive means in accordance with the position of said car with reference to said floor, and a slow-down relay disposed to be operated in 40 response to a predetermined change of the condition of illumination of said light-sensitive means for effecting the stopping of the motor to bring the car to the floor level.

4. In a control system for a motor-operated elevator car movable in a hatchway relative to one or more floors, in combination; a light-controlled unit carried by the car including a light source 45 and a light-sensitive device disposed in operative relation thereto, and a space discharge device disposed to be rendered conducting when said light-sensitive device is not illuminated; a transformer having a primary winding connected to a source of alternating current and a secondary winding, control means operable in response to a floor call and having a plurality of sets of contact members, one of said sets of contact members being disposed to immediately effect the en- 50 70 75

ergization of said light source and another of said sets of contact members being disposed to connect said secondary winding to energize said space-discharge device a predetermined time 5 thereafter, a shield individual to said floor and mounted in the hatchway for intercepting the rays of light falling on said light-sensitive device from said light source, and a slow-down relay disposed to be energized when said space-discharge 10 device is rendered conducting for effecting the stopping of the motor to bring the car to the floor level.

5. In a control system for a motor-operated elevator car movable in a hatchway relative to a 15 floor in which energizing currents due to transient electrical conditions are caused to flow, in combination, light-sensitive means and a light source disposed in operative relation thereto and carried by the car, circuit means for connecting said 20 light-sensitive means to a current source, means for preventing the application to said light-sensitive means of said energizing currents resulting from said transient electrical conditions, a shield individual to said floor and mounted in the hatch- 25 way for intercepting the rays of light falling on said light-sensitive means from said light-source, and a slow-down relay disposed to be operated on the interception of the light rays for effecting the stopping of the motor to bring the car to the 30 floor level.

6. In a control system for a motor-operated elevator car movable in a hatchway relative to a floor, in combination, light-sensitive means and a light source disposed in operative relation thereto and carried by the car, circuit means for connecting said light-sensitive means to an alternating current source, means for preventing the application to said light-sensitive means of frequencies differing from that obtained from said 40 alternating current source, a shield individual to said floor and mounted in the hatchway for intercepting the rays of light falling on said light-sensitive means from said light source, and a slow-down relay disposed to be operated on the 45 interception of the light rays for effecting the stopping of the motor to bring the car to the floor level.

7. In a control system for a motor-operated elevator car movable in a hatchway relative to 50 one or more floors, in combination; a light-controlled unit carried by the car including a light source and a light-sensitive device disposed in operative relation thereto, a space discharge device disposed to be rendered conducting when 55 said light-sensitive device is not illuminated, and a filter connected in circuit with said space-discharge device for preventing the application thereto of currents having frequencies differing from a predetermined frequency; a shield individual to said floor and mounted in the hatchway for intercepting the rays of light falling on said light-sensitive device from said light source, and a slow-down relay disposed to be energized when said space discharge device is rendered 60 conducting for effecting the stopping of the motor to bring the car to the floor level.

8. In a control system for a motor-operated elevator car movable in a hatchway relative to one or more floors, in combination; a light-controlled unit carried by the car including a light source and a light-sensitive device disposed in operative relation thereto, a space-discharge device disposed to be rendered conducting when 70 said light-sensitive device is not illuminated, and a filter connected in circuit with said space-dis- 75

charge device for preventing the application thereto of currents having frequencies differing from a predetermined frequency; a control relay operable in response to a floor call and disposed to effect the energization of said light-controlled unit, a shield individual to said floor and mounted in the hatchway for intercepting the rays of light falling on said light-sensitive device from said light source, and a slow-down relay disposed to be energized when said space-discharge 10 device is rendered conducting for effecting the stopping of the motor to bring the car to the floor level.

9. In a control system for a motor-operated elevator car movable in a hatchway relative to one or more floors, in combination, a light-controlled unit carried by the car including a light source and a light-sensitive device disposed in operative relation thereto, a space-discharge device disposed to be rendered conducting when said light-sensitive device is not illuminated, and a filter connected in circuit with said space-discharge device for preventing the application thereto of currents having frequencies differing from a predetermined frequency; a control relay operable in response to a floor call and disposed to energize said light-controlled unit, means for preventing the application of energizing potential to said space-discharge device until the expiration of a predetermined time after said light source is energized, a shield individual to said floor and mounted in the hatchway for intercepting the rays of light falling on said light-sensitive device from said light source, and a slow-down relay connected in series circuit relation with said space-discharge device and disposed to be energized when said space-discharge device is rendered conducting for effecting the stopping of the motor to bring the car to the floor level.

10. In a control system for a motor-operated elevator car movable in a hatchway relative to a floor, in combination, light-sensitive means and a light source disposed in operative relation thereto and carried by the car, a filter also carried by the car and connected in circuit with said light-sensitive means for preventing the application thereto of currents having frequencies differing from a predetermined frequency, a transformer having a primary winding connected to a source of alternating current and a secondary 50 winding, a control relay operable in response to a floor call and disposed to effect the energization of said light source and to connect said secondary winding to energize said light-sensitive means, a shield individual to said floor and mounted in the hatchway for intercepting the rays of light falling on said light-sensitive means from said light source, and a slow-down relay disposed to be operated on the interception of the light rays for effecting the stopping of the motor 55 to bring the car to the floor level.

11. In a control system for a motor-operated elevator car movable in a hatchway relative to one or more floors, in combination; a light-controlled unit carried by the car including a light source and a light-sensitive device disposed in operative relation thereto, a space-discharge device disposed to be rendered conducting when said light-sensitive device is not illuminated, and a filter connected in circuit with said space-discharge device for preventing the application thereto of currents having frequencies differing from a predetermined frequency; a transformer having a primary winding connected to a source of alternating current and a secondary winding 70
